UNITED STATES PATENT OFFICE.

FERGUS F. WILSON, OF BROOKLYN, NEW YORK, ASSIGNOR TO MERGENTHALER LINOTYPE COMPANY, A CORPORATION OF NEW YORK.

MATRIX AND METHOD OF PRODUCING THE SAME.

1,187,590.

Specification of Letters Patent. Patented June 20, 1916.

Application filed November 10, 1913. Serial No. 800,083.

To all whom it may concern:

Be it known that I, FERGUS F. WILSON, a citizen of the United States, residing at Brooklyn, in the county of Kings and State 5 of New York, have invented certain new and useful Improvements in Matrices and Methods of Producing the Same, of which the following is a specification, reference being had therein to the accompanying 10 drawing.

This invention relates to the production of type matrices for use more particularly in type casting, linotype machines, and the like, and the invention has in view especially 15 the punching of large character matrices, the formation of which has been attended with considerable difficulty by reason of the great amount of metal displaced in the punching operation, and the inability to 20 properly control the direction of the flow of the displaced metal.

It has been particularly difficult to cause the metal to flow up into the counters or cavities in the punch, of such letters as O, 25 R, B, P and the like; and also it has been difficult to prevent the displaced metal from flowing laterally and deforming or distorting the blank. It is of the utmost importance that the counters shall stand at 30 a high level in the matrices to make deep cavities in the type, otherwise these portions of the type standing at a high level will receive ink and transfer it to the paper. It is also of importance that the matrix 35 body preserve its original dimensions and that the character therein occupy accurate and very definite relations to the ends and sides of the same.

The aim of my invention is to obviate the 40 difficulties mentioned, and to form matrices with high counters, without distorting or deforming the body or blank, and the invention consists of an improved means and method of procedure and the matrix produced thereby, in which method the metal of the blank displaced by the punch in the forming action, is allowed to flow into a relief cavity or cavities and in this way be controlled in its direction of flow. As a result 45 the metal of the blank opposite the high points of the punch, will, when the punch is driven into the blank, sink into the relief cavities and will thus be prevented from being displaced laterally and distorting the

blank; while the metal of the blank opposite 55 the depressions in the punch will be supported by the solid metal of the blank beneath, and will be caused to stand up and flow into and completely fill the depressions in the punch and thus form proper high 60 standing counters in the matrix.

In the accompanying drawings I have represented different means embodying my invention and by which my improved method may be carried into effect, but it will 65 be understood that the invention may be embodied in other forms and constructions than those shown, and that the invention is not limited to any particular details or constructions except in so far as such limitations are 70 specified in the claims.

In the accompanying drawings: Figure 1 is a perspective view of the matrix blank-supporting member formed to receive the matrix blank. Fig. 2 is a similar view showing the supporting member and blank separated, and the supporting member provided with relief cavities for the displaced metal of the blank. Fig. 3 is a similar view showing the blank inserted in place in the supporting 75 member. Fig. 4 is a sectional view of the supporting member and blank, and the holding means and forming punch, the parts being in the condition and relative position they occupy previous to the punching operation. Fig. 5 is a similar view showing the punch entered in the blank and with the relief cavities in the supporting member filled with the displaced metal. Fig. 6 is a perspective view of the finished matrix. Fig. 7 80 is a sectional perspective view of the supporting member on a reduced scale showing the relief cavities in modified form. Fig. 8 is a perspective view of the matrix blank 85 showing the relief cavities formed therein instead of in the supporting member.

Referring to the drawings: In carrying my invention into effect I provide a supporting member A, adapted to sustain a matrix blank B, in which the matrix character is to be punched. The supporting member in the example shown is of the general form and contour of the usual and well known circulating linotype matrices as represented for instance in Letters Patent of the United States to Ottmar Mergenthaler, No. 436,532, although in the example illustrated the body is more massive 100 105

to carry larger characters. The matrix blank B, is in the form of a flat plate of suitable material, preferably metal relatively softer than the supporting member 5 so that the matrix may be readily punched therein. The blank B is adapted to be inserted in an open slot or recess a, formed in the edge of the supporting member having a flat supporting bottom surface, and 10 when inserted and subjected to the action of the forming punch, the blank will be caused to expand and be tightly seated in the recess and become so interlocked with the supporting body as to form in effect a part 15 of the same as shown in Fig. 6.

In the punching action, the supporting member with the blank inserted is held in fixed position by any suitable means, in the present instance between clamping jaws C, 20 and the forming punch D, bearing on its lower end the character to be punched in the present instance the letters "P, M," is forced or driven into the blank B, with the result that the metal of the blank will be displaced 25 and will flow laterally as the high points of the punch sink into the blank, forming corresponding depressions therein. By reason of the considerable size of the character on the punch, and the fact that the punching action 30 is a violent one, a great amount of metal is displaced, and as there are no means to control the flow of the displaced metal, it has been found in practice that the blank will become deformed or distorted, and the metal 35 will fail to flow up into and properly fill the counters in the punch, more particularly of such letters as O, R, B, P, and the like. In accordance with my invention I obviate these objectionable actions by providing relief 40 cavities or recesses between the blank and supporting member, by which means the direction of flow of the displaced metal is controlled, being caused to flow in the direction of the action of the punch. As 45 a result, the lateral flow of the metal in such degree as to cause deformation or distortion of the blank, will be prevented, and the portions of the blank between the relief cavities or recesses being supported by the solid 50 metal beneath, will be caused to stand up and completely and properly fill the counters in the punch.

The relief cavities may be of different forms and differently applied. For instance 55 they may take the general form and contour of the character or characters which are to be produced, and be either formed in the bottom of the recess in the supporting member as shown in Fig. 2, or they may 60 be formed in the under face of the blank itself, as shown in Fig. 8. Relief cavities when in this form may be produced by driving the punch a moderate distance into the bottom of the recess in the supporting member, or into the under or reverse side of the

blank, as the case may be. As shown in Fig. 7 and by dotted lines in Fig. 1, the relief cavities may be in the form of a number of sockets D', formed at intervals in the bottom of the recess in the supporting member, 70 or they may be formed in the under face of the blank, their location being preferably opposite the portions of the blank where the high points of the punch will strike in forming the matrix. 75

In carrying my invention into effect when the relief cavities are of the form, and applied as shown in Fig. 2, the blank being inserted in place in the recess over the cavities as shown in Fig. 3, the supporting member and inserted blank are held firmly in fixed position by the clamping jaws C as shown in Fig. 4. The punch is now forced or driven into the blank, with the result that the metal of the blank directly acted on and 80 displaced by the high or relief portions of the punch will flow and sink into the corresponding relief cavities in the supporting member beneath, and the adjacent portions of the blank between and surrounding the 85 high points of the punch will be supported by the solid metal of the supporting body beneath, and these supported portions will be caused to flow up and completely fill the counters in the punch as shown in Fig. 5; 90 at the same time the blank will be expanded and caused to seat tightly in the recess in the supporting member, and a matrix of the form shown in Fig. 6 will be produced. 95

The above described actions will be substantially the same in cases where the relief cavities are formed in the inner or under face of the blank, and also in cases where the cavities are of the form shown in Fig. 7, the relief cavities in all cases serving as a 100 means of relieving the flow of the metal where the greatest displacement takes place, that is, where the high or cameo portions of the punch act, while at the same time the relief cavities serve to control the direction 105 of the flow of the displaced metal, so that the objectionable, undue lateral flow of the displaced metal will be prevented, and the portions of the blank adjacent those acted on by the high points of the punch, will be 110 supported and caused to stand up and properly fill the counters in the punch. 115

While I have shown by way of example the supporting member for the matrix blank in the general form of the well known linotype matrix, and while I have described the practice of my improved method in connection with a supporting member of this form, it will be understood that other forms of supporting members may be employed without departing from the limits of my invention, the form shown adapting the matrix to be employed in connection with the usual and normal sized matrices in linotype machines of the character mentioned. 120 125 130

Having thus described my invention, what I claim is:

1. The method of forming matrices, which consists in providing a matrix body with a recess therein having a flat supporting bottom surface, providing a flat matrix blank having a flat under surface to seat on said bottom surface, one of said surfaces being provided with a relief cavity to receive displaced metal, seating the blank in the recess, and causing said blank, by pressure of a forming punch, to seat flatly against the bottom supporting surface of the recess, and causing the displaced metal to flow into the relief cavity.
2. The method of forming matrices, which consists in providing a matrix body with a recess therein having a flat supporting bottom surface, and a relief cavity in said surface to receive displaced metal, providing a flat matrix blank having a flat under surface to seat on said supporting surface, seating the blank in the recess, and causing the blank, by the pressure of a forming punch, to seat flatly against the supporting surface of the recess, and causing the displaced metal to flow into the relief cavity.
3. The method of forming matrices, which consists in providing a matrix body with a recess therein having a flat supporting bottom surface, and a relief cavity in said surface to receive displaced metal, providing a flat matrix blank having a flat under surface to seat on said bottom surface and having side edges to seat against the walls of the recess, seating said blank in the recess, and causing the blank, by the pressure of a forming punch, to expand and seat at its edges against the walls of the recess to interlock the parts with each other, and causing its under surface to seat against the bottom supporting surface, and the displaced metal to flow into the relief cavity.
4. The improved matrix consisting of a matrix body having a recess therein with a flat supporting bottom surface, a flat matrix blank seated in said recess with its under side resting on and supported by the flat bottom surface, said matrix blank being interlocked with the body and being provided in its upper side with a formative matrix character, one of said parts being provided
5. The improved matrix consisting of a matrix body having a recess with a flat supporting bottom surface and with a cavity in said bottom, a flat matrix blank interlocked with the body and having its under side seated flatly against the bottom surface of the recess, and having a projection thereon extending into the cavity in said bottom, the said matrix blank being provided in its upper face with a formative character.
6. The improved matrix consisting of a matrix body of the general contour of a lino-type matrix, said body having in one edge a recess provided with a flat supporting bottom having a cavity therein, and a flat matrix blank seated in said recess with its under flat side resting against and supported by the bottom of the recess, and with its opposite side flush with the edge of the matrix body, the said matrix blank being interlocked with said body and being provided with a projection extending into the cavity in the bottom of the recess and the upper side of the blank having therein a formative matrix character.
7. The improved matrix consisting of a matrix body of the general contour of a lino-type matrix, said body having in one edge a recess provided with a flat supporting bottom and upper and lower end walls, and said supporting bottom having a cavity therein, and a flat matrix blank seated in said recess with its upper and lower edges bearing against the end walls of the recess, with its under flat side resting against and supported by the bottom of the recess, and with its upper side flush with the edge of the matrix body, the said matrix blank being interlocked with said body and provided with a projection extending into the cavity in the bottom of the recess, and the upper side of the blank having therein a formative matrix character.

In testimony whereof I have affixed my signature in presence of two witnesses.
